(57) **CLAIM**

The ornamental design for a sliding partition panel as shown and described.

DESCRIPTION

FIG. 1 is a front and right perspective view of a sliding partition panel, showing our new design.

FIG. 2 is a front elevation view thereof. A rear elevation view is identical to the front elevation view.

FIG. 3 is a right side elevation view thereof. A left side elevation view is identical to the right side elevation view.

FIG. 4 is a top plan view thereof.

FIG. 5 is a bottom plan view thereof.

FIG. 6 is a cross sectional view thereof, taken along the line 6-6 in FIG. 2.

FIG. 7 is an enlarged view of the portion defined by arrows 7 in FIG. 6.

FIG. 8 is an enlarged view of the portion defined by arrows 8 in FIG. 6.

FIG. 9 is referential view showing use thereof.

FIG. 10 is an enlarged view of the portion defined by the area 10 in FIG. 1.

FIG. 11 is an enlarged view of the portion defined by the area 10 in FIG. 2; and,

FIG. 12 is an enlarged view of FIG. 5.

The broken lines shown in the drawings illustrate portions of the sliding partition panel that form no part of the claimed design.
